2,127,686

SNAP SWITCH

Clarence John Hathorn, St. Marys, Pa., assignor
to The Stackpole Carbon Company, St. Marys,
Pa., a corporation of Pennsylvania

Application January 7, 1937, Serial No. 119,375

7 Claims. (Cl. 200—67)

My invention relates to a control for an electric circuit and relates particularly to a snap switch for completing or interrupting the electrical circuit at the option of the operator.

In my prior patent application Serial No. 701,802, filed December 11, 1933, I have disclosed a pivoted bridging member which makes a good contact with the stationary contact terminals even though there is a slight variation of the throw arm or the fixed terminals from their predetermined correct position.

In certain switches where the circuit is completed by the bridging of two fixed or stationary terminals by a non-pivotal bridging member, the incorrect positioning of one or both of the fixed terminals may result in one portion of the bridging member being spaced a small distance from one of the terminals. This spacing of the bridging element from the live terminal results in an arc being established between the separated live elements with its destructive result of eroding or pitting of the electrical contact surfaces which establishes a high resistance and also reduces the effective life of the switch, since the terminals and/or the bridging member will be burned away.

Further, in switches where the throw arm is pivotally mounted and where the bridging member is pivotally rotated into bridging position, the force or torque imparted to the bridging member by the throw arm is normal to an imaginary radius drawn between the point of application of the force and the pivot point. However, if the pintle or pivot for the bridging member is comparatively near to the turning force (that is the throw arm), then a freezing or sticking of the electrical bridging member makes the device inoperative.

Therefore, an object of my invention is to construct a snap switch which will not stick and which will be effective in operation even though some elements may be improperly aligned during the course of manufacture.

It is a further object of my invention to minimize the sparking or arcing between the terminals and their cooperative bridging member.

It is another object of my invention to provide a frictional or sliding or wiping contact between the stationary electrical terminals and the movable electrical bridging member whereby the terminals will always be kept clean or will of themselves brush aside any dust or dirt that may collect thereon.

Another object of my invention is to obtain a very low contact resistance between the bridg-

ing member and the terminals. As a corollary, an object of my invention is to minimize the heating of the elements of the switch by reducing the contact resistance.

A still further object of my invention is to simplify the construction of the device so that it may be manufactured in quantity lots at a low cost.

A still further object of my invention is to construct an interfitting elongated recess or opening on a bridging member which is cooperative with a pin whereby the pressure of each side of the bridging member may be equalized or evenly distributed when the bridging member is in closed circuit position.

Other objects of my invention are to provide an improved device of the character described, which is simple and economical in construction, and which possesses a maximum amount of serviceability and of strength.

With the above and related objects in view, my invention consists in the details of construction and the combination of parts that will hereinafter be fully described when the description is read in conjunction with the accompanying drawings in which:

Fig. 1 is a plan view of a snap switch embodying my invention.

Fig. 2 is a sectional view taken on the line 2—2 of Fig. 1.

Fig. 3 is an exploded view of the elements comprising the snap switch.

Fig. 4 is a diagrammatic view of a bridging member which can only be oscillated and wherein a terminal shown in dotted lines is incorrectly located. The diagram shows a main contact surface of the bridging member being spaced from the incorrectly aligned stationary contact terminal.

Fig. 5 is a diagrammatic view of a bridging member which can be oscillated and which also can be moved in a linear direction to properly engage fixed contacts—one of said contacts being improperly aligned.

Fig. 6 is a fragmentary sectional view showing my improved switch connected to a volume control or rheostat.

Fig. 7 is a side view of a modification of my invention.

Fig. 8 is a front view of Fig. 7.

Fig. 9 is an exploded view of another modification of the bridging member and the insulating bushing.

Fig. 10 is an exploded view of still another

modification of the bridging member and throw arm.

Fig. 11 is a fragmentary sectional view of a modification of the base having a molded pintle therein about which the electrical bridging member oscillates.

Referring now in greater detail to the drawings, in Fig. 1 is shown a type of snap switch wherein the overall diameter of the switch is approximately 1 1/8 inches and the overall thickness of the base is approximately 1/4 inch. The switch mechanism hereinafter further described is mounted within a chamber of an insulated base, generally designated A, which is preferably comprised of a molded phenolic condensation product. A body portion 10 of the base is substantially flat and from its periphery extends a flange 12 which is substantially circular on its outer bounding surface. The flange has a plurality of recesses or notches 14, 15, and 16 on its inner curved portion, and the recesses or notches communicate directly with the central chamber of the base. The function of the notches 14, 15, and 16 will be herein-after described in conjunction with the various 25 elements which they complement.

A plurality of small openings 18, 19, 20, 21, 22 and 23 are formed in the base. The surface defining the opening 22, centrally located in the base, serves as a bearing for a freely longitudinally 30 movable insulating pin or pintle, generally designated as B. The insulating pintle B comprises a cylindrical shaft 24 and an enlarged head 26. An electrical bridging member or blade, generally designated as C, oscillates about the shaft of the 35 equalizing pintle B as its pivot, and it also supports an insulating washer, generally designated as D.

The enlarged head 26 is pressed downwardly by a throw arm, generally designated as E, which 40 presses on the upper surface of the head 26, thus preventing the bridging member from falling out of position. The washer D serves as an electrical insulator between the steel throw arm E and the spring H, which is on one side, and the metallic 45 bridging member, which is on the other side.

Openings 21 and 23 are spaced from one another on the circumference of an imaginary circle which has its center substantially in the central axis of the opening 22, and the openings 21 and 50 23 receive the shank of each of the electrical conducting rivets 28 and 30.

Each of the electrical conducting rivets 28 and 30 are similarly constructed so that a description of one rivet or contact will suffice as the description of all the rivets or terminals. Rivet 28 has an enlarged intermediate portion 31 which is flat on one side and abuts against the base, and its upper surface (the auxiliary or arcing stationary contact) is formed in the shape of a truncated 55 cone, and from the smaller diameter of the truncated cone extends the bridging member contact portion 32 (the main stationary contact). The purpose and function of this structure is more fully set forth in my prior patent application 60 Serial No. 701,802, filed December 11, 1933, which I have already mentioned.

The outside of the shank of the rivet 28 is expanded to hold a terminal 34 to which exterior terminal 34 a flexible electrical lead wire may be 70 soldered or otherwise suitably attached thereto.

The end of the rivet 28 adjacent the outside terminal 34 is expanded to retain the rivet and terminal 34 firmly together, and also establishes a good electrical contact between the rivet and the 75 terminal. The openings 19 and 20 serve as open-

ings for rivets which retain the snap switch to a volume control or rheostat which forms a combined volume control and snap switch unit, both devices usually being operated by a single control shaft. The switch is usually operated at a predetermined portion of movement of the control shaft.

A trigger and bridging member pivot or pintle, generally designated as F, is located within the recess 14 and is of the type described in my prior Patent No. 2,057,829, granted October 20, 1936. Upon the pintle F is pivotally mounted the metallic throw arm E as well as a trigger, generally designated as G, the latter being the actuated element of the snap switch whereby the switch is 10 operated to open or to closed circuit positions. The throw arm E is located between the trigger G and the base, and the metallic arm E has its free end 34 slightly offset from its pivotally held end 20 36.

An opening 38 on the longitudinal axis and adjacent one end of the throw arm is substantially circular and is of a diameter to readily fit over the largest diameter of the pintle, in order to expedite the assembly of the throw arm of the 25 pintle during the steps in assembling the elements of my snap switch. The circular opening 38 merges with an elongated slot 39 which is of a width whereby it may oscillate or pivot about the bearing F. A small central opening 40 in the longitudinal axis of the throw arm receives a bushing 42, the bushing in turn receiving the tip 44 of one leg of the torsional spring, generally designated as H.

An elongated opening 46 on the end 34 of the 35 throw arm receives an insulating bushing 48, and the bushing 48 is constructed so that its diameter is less than the width of the opening 46. However, a head 50 of the insulating bushing is of greater width than the width of the opening 40 so that the bushing cannot pass through the throw arm opening 46.

The bore 52 of the bushing receives the end or tongue 54 of the lever arm 56 of the bridging member C. The bridging member or blade 45 C has a substantially flat central portion 58 and offset contacting arms 60 and 61.

The movable arm 61 has an auxiliary or arcing surface 61A, which surface first engages the auxiliary stationary contact 31 where the arc 50 is made, and the vertically extending front or main contact surface 61B engages the main stationary contact 32. When the contacts are separated, the auxiliary stationary contact 31 and the arcing surface 61A are the last surfaces to separate thus taking the arc, hence preserving the main contact surfaces. An arrangement similar to the above is made for the stationary terminal 30 and the movable arm 60.

From the central portion 58 of the electrical 60 blade C extends the lever arm 54 which is at right angles to the contact arms 60 and 61. An elongated rectangular-like slot or opening 62 cooperatively receives the insulating pintle B, and the length of the slot 62 is longer than 6 the diameter of the pintle shank 24. This is for the purpose of having the blade move in a linear direction. The elongated slot 62 has its longitudinal axis disposed at an acute angle with respect to the line joining the main contact 7 surfaces 60B and 61B of the blade C. This angular construction of the slot 62 prevents any sticking of the pintle B and the surfaces defining the slot 62.

It is to be observed at this point that the sta- 7

tionary terminals 28 and 30 limit the movement of the bridging member C in a clockwise direction which also is the position of the bridging member when the circuit is closed, and the throw arm E and wall 10 limit movement of the bridging member C when it is moved in a counterclockwise direction. The bridging element C may not only oscillate about pintle B, but it may move in a linear direction with respect to the pintle B. The above described construction and function of the bridging member is important in the following respect: Assume that the holes 21 and 23 are not located properly with respect to the pintle B in the base A so that terminals 28 and 30 will be located in the position 28 and 30X, diagrammatically illustrated in Fig. 4. If a slight space existed between the bridging member and one of the terminals in the base, then one of the terminals would not receive the full movable contact pressure since the other terminal would prevent movement of the throw arm in a rotary direction, and when current flows, an arc would exist in the space, hence pitting the contacts. However, with an equalizing arrangement such as the elongated angularly disposed slot 62, illustrated diagrammatically in Fig. 5, then the bridging member C is not constrained by its pintle or the lever arm but is free to move in a linear direction because of the respective elongated slots 62 and 46.

By the above structure, it is readily seen that errors committed in assembling the unit or in constructing the elements of the switch will not result in excessive pitting of the terminals or the bridging member with its detrimental effect of creating high resistance and shortening the life of the switch.

A flat torsional expansion spring H having a central portion coiled has one tip 44 enter the bushing 42, and the other tip 64 enter an opening in the notch formed at the free end of the trigger G. The torsional spring not only imparts rapid movement or snap action to the throw arm when the trigger G is moved to a point whereby the dead center position of the spring is reached, but the torsional spring H tends to press the throw arm in a direction towards the base. This dual effect of the spring keeps the throw arm pressed upon the head of the pintle B. The trigger G has upturned arms 66 and 67 which are engaged by an eccentrically positioned pin 71 which may be on an insulating plate 72 of a volume control, generally designated as V, as shown in my prior issued Patent No. 2,057,839.

In order to actuate the snap switch, either the arm 66 or the arm 67 of the trigger may be engaged by the eccentrically mounted pin 71 which projects normally to the plane of the volume control insulating disc 72 depending on the position of the eccentrically mounted pin and the position of the ears 66 or 67.

A washer 69 is placed adjacent the metallic trigger G, and the upper end of the trigger pin F is peened over to hold the trigger and throw arm in position.

It is to be observed that the coiled portion of the spring H which tends to exert an expansive force freely moves in the recess 15. The tip 34 of the throw arm moves in the recess 16 and a wall 10, partially defining the recess 16, engaged by the side of the throw arm when the switch is in open circuit position limits the movement of the throw arm when the throw

arm E, Fig. 1, is moved in a counterclockwise direction.

In Figs. 7 and 8, I show a modified construction of my improved snap switch wherein the elements designated by the same reference character or numeral as those shown in Fig. 3 are of similar construction. However, the toggle trigger J is substantially flat and has an opening in one end 80, which opening receives a portion of the torsional spring H, and two spaced arms 82, 83 extend outside of the flange 12 but in the same plane as the flat body portion 80.

Fig. 9 shows another modification of my invention showing an insulating bushing which serves as a pivotal connection between the metallic throw arm E and the oscillatory blade C1. The electrical conducting bridging blade C1 moves around a central pivot or pintle B and has its turning force applied to a lever arm 90 which extends substantially in the same plane as the major portion of the bridging member.

In other words, the lever arm 90 extends substantially parallel to the throw arm E. An insulating pivot K has an enlarged portion 92, and the transverse end has a slot 94 which receives the lever arm 90 of blade C1. A narrow circular portion 96 on the pin K interfits with the elongated slot 46 in the throw arm whereby the pin K may slide bodily the entire length of the throw arm opening 46.

The diameter of the enlarged portion 92 is greater than the width of the slot 46 so that the pin does not pass through the slot. The pressure on the throw arm by the torsional spring prevents the various elements from separating from their operative relationship. The main contact surfaces 60C and 61C on bridging member C1 are arranged similarly to the main contact surfaces 60B and 61B on blade C. The slot 62C is arranged similarly to the slot 62 on blade C.

In Fig. 10 I illustrate another modification of my invention wherein the throw arm E1 has two depending ears 96 and 98 which are stamped from the ends of the throw arm E1. The depending arms 96 and 98 straddle the extending lever arm 100, and the tip 102 of the throw arm serves as the limiting member. A piece of insulation 104 can be forced on arms 96 and 98 so that the metallic arm E1 will be insulated from the bridging member C2.

In Fig. 11 I show a modification of the molded base wherein a pintle or stud 106 is integrally formed with the base, and the pintle 106 interfits with an opening in the bridging member C.

Although my invention has been described in considerable detail, such description is intended as illustrative rather than limiting, since the invention may be variously embodied, and the scope of the invention is to be determined as claimed.

I claim as my invention:

1. A snap switch comprising an insulating base, a pivot, a forked trigger pivotally mounted on said pivot, a metallic throw arm pivotally mounted at one end and having an elongated opening 65 at the other end, means between said trigger and said throw arm for pressing said throw arm in a direction towards the base and for imparting rapid movement to said throw arm when said trigger is moved to a predetermined position, a plurality of fixed electrical terminals mounted on said base, an electrical bridging member for engaging said terminals whereby the circuit will be closed, a pintle on said base located between said terminals, said bridging member having an 75

enlarged opening therein for receiving said pintle, a lever arm connected to said bridging member, and an insulating bushing movably mounted in the opening of said throw arm and receiving a portion of said lever arm whereby movement of said throw arm will oscillate said bridging member, said enlarged openings on said throw arm and said bridging member enabling the bridging member to exert equal pressure on each terminal when the switch is in closed circuit position.

2. A snap switch comprising an insulated base, a plurality of stationary electrical terminals mounted in said base, an electrical bridging member having a lever arm, said bridging member adapted to engage and to be disengaged from said stationary terminals, an insulating pintle having an enlarged head, said pintle loosely mounted in said base and about which said bridging member oscillates, said bridging member having an enlarged opening which cooperatively receives the insulating pintle, the enlarged head of said pintle pressing the bridging member in a direction towards the base, a throw arm and a trigger each of which is pivotally mounted, a spring connected between said trigger and said throw arm whereby rapid movement will be imparted from said trigger to said throw arm, said spring also being adapted to press the throw arm in a direction towards the head of said pintle, and said throw arm having an elongated opening to loosely receive the lever arm of said bridging member whereby said bridging member exerts equal pressure on each terminal when the switch is in closed circuit position.

3. A snap switch comprising an insulating base, a forked trigger pivotally mounted, a metallic throw arm pivotally mounted, a torsional spring between said trigger and said throw arm for pressing said throw arm in a direction towards the base and also for imparting rapid movement to said throw arm when the trigger is moved to a predetermined point; a plurality of fixed electrical contact terminals, a pintle on said base located between said terminals, an electrical bridging member for engaging said terminals to close the circuit, an insulating bushing, said bushing interfitting with an elongated opening in the free end of said throw arm, said bridging member having an enlarged opening for receiving said pintle, a lever arm connected to said bridging member, and a portion of said lever arm interfitting with said bushing in said throw arm whereby movement of said throw arm will oscillate said bridging member about said pintle so that the pressure on the terminals will be equalized when the switch is in closed circuit position.

4. A snap switch comprising an insulating base, a forked trigger pivotally mounted, a metallic throw arm pivotally mounted at one end and having an elongated opening at the other end, means between said trigger and said throw arm for pressing said throw arm in a direction towards the base and for imparting rapid movement to said throw arm when said trigger is moved to a predetermined position, a plurality of fixed electrical terminals mounted on said base, an electrical bridging member for engaging said terminals whereby the circuit will be closed, a pintle on said base located between said terminals, said bridging member having an enlarged open-

ing therein for receiving said pintle, a lever arm connected to said bridging member, and an insulating bushing movably mounted in the opening of said throw arm and receiving a portion of said lever arm whereby movement of said throw arm will oscillate said bridging member, said enlarged openings on said throw arm and said bridging member enabling each contact member of the bridging member to exert equal pressure on each terminal when the switch is in closed circuit position.

5. A snap switch comprising an insulated base, a plurality of stationary electrical terminals mounted in said base, an electrical bridging member having a lever arm, said bridging member adapted to engage and to be disengaged from said stationary terminals, an insulating pintle having an enlarged head and loosely mounted in said base and about which pintle said bridging member oscillates, said bridging member having an enlarged opening which cooperatively receives the insulating pintle, the enlarged head of said pintle pressing the bridging member in a direction towards the base, a throw arm and a trigger each of which is pivotally mounted, a spring connected between said trigger and said throw arm whereby rapid movement will be imparted from said trigger to said throw arm and also to press the throw arm in a direction towards the head of said pintle, an insulating bushing interfitting with an elongated opening of said throw arm, a portion of the lever arm on said bridging member interfitting with said insulating bushing, said bridging member adapted to exert equal pressure on each terminal when the switch is in closed circuit position.

6. In an electrical switch, an electrical conducting bridging member having offset blade arms, a rectangular-like opening in the center of said bridging member, a pivot interfitting with said rectangular-like opening whereby said bridging member may oscillate or move in a linear direction, an integrally formed lever arm on said bridging member, the tip of said lever arm upturned, means to move said tip whereby the bridging member may be oscillated, and terminals arranged to be bridged by said bridging member.

7. A snap switch comprising an insulating base, a forked trigger pivotally mounted, a throw arm pivotally mounted, a spring connected between said trigger and said throw arm for pressing said throw arm in a direction towards the base and also for imparting rapid movement from the throw arm when the trigger is moved to a predetermined point, a plurality of fixed electrical terminals, a pintle on said base positioned between said terminals, an electrical bridging blade for engaging said terminals to close the circuit or to be disengaged from said terminals to open said circuit, an insulating bushing, said bushing interfitting with an elongated opening in the free end of said throw arm, said bridging blade having an enlarged opening for receiving said pintle, a lever arm connected to said bridging blade, said lever arm being substantially parallel to said throw arm, and a portion of said lever arm interfitting with a recess in said bushing whereby movement of said throw arm will oscillate said bridging blade about said pintle.

CLARENCE JOHN HATHORN. 70
